(57) **CLAIM**

The ornamental design for a bench, as shown and described.

DESCRIPTION

FIG. 1 is a perspective view showing a front, top and side of a first embodiment of a bench;

FIG. 2 is a front elevational view of the first embodiment of the bench;

FIG. 3 is an elevational view of a side of the first embodiment of the bench, the opposite side being a mirror image thereof;

FIG. 4 is a rear elevational view of the first embodiment of the bench;

FIG. 5 is a top plan view of the first embodiment of the bench;

FIG. 6 is a bottom plan view of the first embodiment of the bench;

FIG. 7 is a perspective view showing a front, top and side of a second embodiment of a bench;

FIG. 8 is a front elevational view of the second embodiment of the bench;

FIG. 9 is an elevational view of a side of the second embodiment of the bench, the opposite side being a mirror image thereof;

FIG. 10 is a rear elevational view of the second embodiment of the bench;

FIG. 11 is a top plan view of the second embodiment of the bench;

FIG. 12 is a bottom plan view of the second embodiment of the bench;

FIG. 13 is a perspective view showing a front, top and side of a third embodiment of a bench;

FIG. 14 is a front elevational view of the third embodiment of the bench;

FIG. 15 is an elevational view of a side of the third embodiment of the bench, the opposite side being a mirror image thereof;

FIG. 16 is a rear elevational view of the third embodiment of the bench;

FIG. 17 is a top plan view of the third embodiment of the bench; and,

FIG. 18 is a bottom plan view of the third embodiment of the bench.

The broken away sections shown in the drawings are understood to represent indefinite widths.
